(57) **CLAIM**

The ornamental design for a combination glove and electronic device holder, as shown and described.

DESCRIPTION

FIG. 1 is a top perspective view of a combination glove and electronic device holder, showing the new design shown receiving an electronic device;

FIG. 2 is a top perspective view thereof shown with an electronic device removed;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof;

FIG. 9 is a cross-sectional view taken from the cut indicated in FIG. 3;

FIG. 10 is a top perspective view of an alternate embodiment of FIG. 1 shown receiving an electronic device; and,

FIG. 11 is a top perspective view shown with an electronic device removed thereof.

The broken line electronic device in FIGS. 1 and 10 represents environment. The remaining broken lines illustrate portions of the combined glove and electronic device holder. The dash-dot broken lines in FIG. 9 illustrate the cross sectional view. None of the broken lines form part of the claimed design.
